LOCKING FIXTURE

Guy E. Swartz, Detroit, Mich.

Application October 6, 1941, Serial No. 413,857

4 Claims. (Cl. 90—59)

The present invention relates to locking fixtures for use in production of machine parts, for example, in fixing parts to be subjected to multiple drilling or other operations.

In the use of such fixtures for so-called "heavy duty" operations, where the part being worked is large and requires large clamping means, it has been found that the quite heavy movable member of the clamp is difficult to move up and down and consequently subjects the operator and the operating parts to undue strains.

It is among the objects of the present invention to provide means for overcoming such difficulties by the use of weight compensation means acting on the heavy clamp element.

Another object is a weight compensation means which may be adjusted both for tension and for considerable variation in the dimension of the part to be clamped.

Other objects and advantages will readily occur to those skilled in the art upon reference to the following description and the accompanying drawing in which

Figure 1 is a perspective view of a locking fixture embodying the invention.

Figure 2 is a longitudinal central vertical sectional view of the base portion.

Figure 3 is a section on line 3—3 of Figure 2.

As indicated in the drawing, a fixture embodying the present invention may consist of a base 10 having at each end guide sleeves 11 through which and into the base extend vertically slidable rack members 12 fixed at their upper ends to a clamping plate 13.

Extending longitudinally through the base 10 is a shaft 14, mounted in suitable bearings in the end walls, and provided with teeth at the portions adjacent racks 12 for engaging the teeth of the latter, so that rotation of shaft 14 provides up and down motion of plate 13.

Rotation of the shaft 14 is accomplished by means of a lever 15 acting through self-locking means indicated as a whole at 16, the detailed construction of which is not being shown, but which provides for turning the shaft and locking it automatically against reverse motion.

Since as stated above, the members 12 and 13 in heavy duty fixtures are quite heavy, a weight compensation means is shown as included in the structure. This compensator is shown as a heavy helical spring 20, fixed at one end 21 to shaft 14, and at its other end secured to a sleeve 22 rotatably mounted on shaft 14.

This sleeve 22 is provided on its outer surface with worm teeth 23 adapted to coact with a worm

24 formed on a shaft 25 mounted in suitable bearings in the back and front walls of the base 10, and extending through the latter to the outside, the projecting end being squared or otherwise shaped as at 26 to permit application of a suitable handle (not shown).

In mounting the shaft 25, it is preferred to provide its forward bearing in a bushing 27 fixed in the front wall of the base as by a screw 28.

10 In operation, the fixture is adjusted so that the plate 13 is at approximately the proper height for the work part to be operated, the tension of spring 20 is then adjusted to counterpoise the weight of the vertically movable parts. Under 15 such an adjustment, operation of the hand lever 15 provides a smooth easy action even in the largest and heaviest fixtures. The locking means 16 may be of any suitable form, but is preferably such as is shown in my previous U. S. Patent No. 2,171,458, issued August 29, 1939, or No. 2,066,167, issued December 29, 1936.

Now having described the invention and the preferred embodiment thereof, it is to be understood that said invention is to be limited, not to 25 the specific details herein set forth, but only by the scope of the claims which follow.

I claim:

1. A locking fixture including a base, a clamping plate located above said base, rack members 30 fixed to said plate and extending into said base, a shaft rotatably mounted in said base and provided with pinions coacting with said rack members to move said plate, means for rotating and for locking said shaft in position, and means for counterbalancing the weight of said plate and racks.

2. A locking fixture including a base, a clamping plate located above said base, rack members fixed to said plate and extending into said base, 40 a shaft rotatably mounted in said base and provided with pinions coacting with said rack members to move said plate, means for rotating and for locking said shaft in position, and spring means adapted to act upon said shaft to provide 45 a resilient resistance to its rotation toward clamping position.

3. A locking fixture including a base, a clamping plate located above said base, rack members fixed to said plate and extending into said base, a 50 shaft rotatably mounted in said base and provided with pinions coacting with said rack members to move said plate, means for rotating and for locking said shaft in position, and means for counterbalancing the weight of said plate and racks, said 55 latter means consisting of a spring fixed to said

shaft and to said base and biased to resist rotation of said shaft to clamping position.

4. A locking fixture including a base, a clamping plate located above said base, rack members fixed to said plate and extending into said base, a shaft rotatably mounted in said base and provided with pinions coacting with said rack members to move said plate, means for rotating and for locking said shaft in position, and a spring coacting with said shaft for counterbalancing the

5 weight of said plate and racks, means for fixing one end of said spring to said shaft, and means for fixing the other end of said spring to said base and adjusting the tension thereof, said latter means consisting of a sleeve rotatable upon said shaft and provided with worm gear teeth and a worm shaft mounted in said base and coacting with said worm gear on said sleeve.

10
